UNITED STATES PATENT OFFICE.

CARL J. ULMANN, OF NEW YORK, N. Y.

DESIGN FOR AN ORNAMENTAL TRIMMING-CORD.

SPECIFICATION forming part of Design No. 29,693, dated November 15, 1898.

Application filed October 18, 1898. Serial No. 693,929. Term of patent 7 years.

To all whom it may concern:

Be it known that I, CARL J. ULMANN, a citizen of the United States, residing in the city of New York, borough of Manhattan, county and State of New York, have invented and produced a new and original Design for an Ornamental Trimming-Cord, of which the following is a specification.

The leading feature of my design is an ornamental trimming-cord presenting the variegated effect of adjacent polygons of braided cloth or ribbons of various colors or shades, as exhibited in the accompanying drawings, in which—

5 Figure 1 is a plan, and Fig. 2 a cross-section,

which illustrate an ornamental cord embodying my design.

In the drawings, *a* is a cord having on its surface a straight tubular covering comprising polygons *b* of various shades, the whole 20 presenting the effect of a tube of braided cloth or ribbons.

What I claim is—

The design for an ornamental trimming-cord substantially as herein shown and described. 25

CARL J. ULMANN.
